UNITED STATES PATENT OFFICE.

VINCENT C. DE YBARRONDO, OF LOS ANGELES, CALIFORNIA.

TELEGRAPHIC SOUNDER.

No. 901,861.

Specification of Letters Patent.

Patented Oct. 20, 1908.

Application filed May 6, 1907. Serial No. 372,126.

To all whom it may concern:

Be it known that I, VINCENT C. DE YBARRONDO, a citizen of the United States, residing at Los Angeles, in the county of Los Angeles and State of California, have invented new and useful Improvements in Telegraphic Sounders, of which the following is a specification.

This invention relates to a sounder for telegraph systems, and it relates more particularly to an attachment that is adapted to be substituted for the gong of an electric bell, whereby the hammer can be used for giving the sounds.

The invention has for one of its objects to improve and simplify the construction of devices of this character so as to be easy and inexpensive to manufacture, readily applied to an ordinary electric bell, and thoroughly satisfactory in service.

A further object of the invention is the provision of an attachment that is adapted to be applied to the base-plate of the electric bell outfit in such position that the hammer can strike against the same for producing the sounds for receiving a message, thus enabling a simple form of bell to be converted into a telegraphic sounder.

With these objects in view and others, as will appear as the description proceeds, the invention comprises the various novel features of construction and arrangement of parts which will be hereinafter more fully described and set forth with particularity in the claims appended hereto.

In the accompanying drawing, which illustrates one of the embodiments of the invention, Figure 1 is a plan view of an electric bell with the casing removed and the attachment in section, and showing the electrical connections. Fig. 2 is a section of the attachment or member against which the hammer on the bell strikes. Fig. 3 is a plan view of the attachment.

Similar reference characters are employed to designate corresponding parts throughout the several views.

Referring to the drawing, 1 designates the base-plate to which the frame 2 of an ordinary electric bell mechanism is attached, said mechanism comprising electro-magnets 3, a spring-pressed armature 4, having a hammer or striker 5 formed on the extension 6 of the armature. The frame 2 is secured to the base 1 by a single screw 7 that permits of the frame to be readily adjusted

with respect to the attachment so as to bring the hammer 5 in proper relation to the latter. The attachment or member 8 against which the hammer strikes comprises a strip 60 of brass or other suitable material that is bent into the general form of a U, with the extremities of the arms 9 apertured for receiving a bolt 10, whereby the arms can be adjusted to or from the hammer 5. The bottom of the U-shaped member is provided with an aperture 11 for receiving a screw 12, whereby the member is attached to the base 1.

In connecting the device in an electric circuit for receiving messages, the binding post 13 alone is employed and this post is connected with the electro-magnets 3 on one side by the conductor 14 with the ordinary Morse key 15 on the other side and from the Morse key extends a conductor 16 connected with a battery 17, the negative side of the battery being connected by a conductor 18 with the post 19 that usually carries a platinum pointed screw when the mechanism is connected up for ringing as a bell. This screw is dispensed with in the present instance and the conductor 18 is soldered or otherwise suitably secured to the member 19, the latter being also connected with the 85 electro magnets in the usual manner. By manipulating the key 15, the circuit can be opened and closed, thereby energizing the electro-magnets and causing the armature to operate as an ordinary sounder by striking the sounding member or attachment 8. It will thus be seen that a very simple and inexpensive telegraphic sounder can be made out of a simple form of electric bell with comparatively little trouble and at the same 95 time produce a device that can be satisfactorily used for telegraphing.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired, as are within the scope of the claims. 110

Having thus described the invention, what I claim is:—

1. In a telegraphic sounder, an attachment comprising a U-shaped metallic member, and means for adjusting the arms of the member, in combination with a hammer disposed between the arms and between the said means and bottom of the member.
2. In a telegraphic sounder, an attachment comprising a U-shaped metallic member, and a bolt adjustably connecting the extremities

of the member together, in combination with a hammer arranged to strike directly on the member.

In testimony whereof, I affix my signature in presence of two witnesses.

VINCENT C. DE YBARRONDO.
